UNITED STATES PATENT OFFICE.

MELVIN VANIMAN, OF ATLANTIC CITY, NEW JERSEY, ASSIGNOR TO INTERNATIONAL AERONAUTICAL CONSTRUCTION COMPANY, A CORPORATION OF MAINE.

PROCESS OF MAKING BALLOONS.

1,081,792.

Specification of Letters Patent. Patented Dec. 16, 1913.

Application filed March 19, 1912. Serial No. 684,824.

To all whom it may concern:

Be it known that I, MELVIN VANIMAN, a citizen of the United States, and a resident of Atlantic City, in the county of Atlantic 5 and State of New Jersey, have invented new and useful Improvements in Processes of Making Balloons, of which the following is a specification.

In an application filed by me on January 10, 29th, 1912, under Serial No. 674,009, I have described a balloon consisting of an inner gas bag, a series of longitudinal strips of fabric thereon containing parallel wires running lengthwise of the structure and a helical winding of the same fabric superposed on the longitudinal strips, thus giving great strength to the structure against both longitudinal and circumferential strains.

The object of my present invention is to 20 devise a balloon and a method of building the same by which the inner gas bag forms no part of the final balloon, thus decreasing the total weight of the balloon by the weight of the bag, and to also change the structure 25 of the balloon, which now principally consists of two wired layers, to make it better able to withstand the action of the inflating gas upon it, all of which will soon appear from the following drawings, in which—

30 Figure 1 is a side elevation of the forming bag. Fig. 2 is a side elevation of this bag with the longitudinal strips of fabric applied thereto. Fig. 3 is a side elevation of the balloon with the helical winding of wire 35 fabric superposed upon the longitudinally applied strips. Fig. 4 is a cross-section showing the lap-joint between the layers. Fig. 5 is a cross-section of a piece of the balloon structure showing two layers of the 40 forming bag and the two layers of the balloon. Fig. 6 is a diagrammatic cross-section of the fabric from which the balloon is made. Fig. 7 is a cross-section, at right angles to the axis of the balloon, showing 45 the forming bag deflated. Fig. 8 is a cross-section of the air lock and means for inflating. Fig. 9 is a face view of the devices for closing the hole shown in Fig. 8, and Fig. 50 10 is a cross-section thereof.

The forming bag A has connected thereto an inflating pipe or extension tube A' which can be constricted and hermetically closed at A². I cover this inflated forming bag 55 B', as shown in Fig. 2, and I cement and

overlap the edges B³ of this fabric, to secure greater strength, as shown in Fig. 4. Thereupon I wind upon the balloon a helical series of turns of the same fabric, as at B², with the edges also cemented and overlapped, and such winding I preferably effect by the apparatus shown in my application Serial No. 684,825, filed March 19, 1912. In fact, as will appear from that application, I vulcanize the outer helical layer to the inner layer so that these two layers form, in effect, an integral mass or structure.

The fabric B which I preferably employ is shown in cross-section in Fig. 6 and consists of parallel, longitudinal wires B⁵ as 70 well as longitudinal threads of ramie fiber B⁶ and of wefts of cotton thread B⁷. The piano wire gives enormous strength and this is helped to a considerable extent by the ramie fiber. The cotton weft, however, is 75 useful because it takes the vulcanizing material and I may use as a substitute for such cotton any other thread which takes vulcanizing compound. Since the strain in elongated balloons in a circumferential 80 direction is about twice that which exists longitudinally, I use the wires or ramie fiber of appropriate size and number to produce twice the tensile strength in the helical layer as in the longitudinal layers. My fabric, it 85 will be observed, has the strength giving strands, whether of wire or fabric, in the longitudinal direction only. My elongated balloon is thus made of maximum strength for the minimum of weight by the expedient of the two longitudinal and helical layers of fabric, with about twice the tensile strength in the helical winding.

I now have a forming bag inflated with air and a balloon structure consisting of two crossed layers of fabric intimately united and lying upon the forming bag. It becomes necessary to coat the inside of this balloon structure with a substance which will prevent the gas, with which the balloon is finally inflated, from escaping therethrough. To this end I permit the forming bag to become deflated by allowing air to escape from it by partially removing the constriction at A². But if this were all, the 100 pressure of the external atmosphere would cause the balloon structure to collapse. This would bend and distort the wires therein contained to such an extent as to rob the balloon of the very strength these wires are 110

intended to impart upon subsequent inflation. To avoid this I cause air, under pressure, to be forced into the space between the outside of the forming bag and the inside 5 of the balloon structure at the same rate at which the air leaves the forming bag. In fact matters are so arranged that the pressure of the air entering between the forming bag and the balloon structure drives 10 the air out of the forming bag, which insures that the inside pressure keeping the balloon from collapsing is always at work. To effect this result, I cut an aperture in the balloon, but, in order that the strength may 15 not be impaired by the consequent cutting of the wires, I apply to the opening two rings C C' which clamp the two layers of the balloon fabric firmly therebetween. I may use projections C² on one of the rings 20 taking into a countersink on the other ring to more effectively prevent the wires from pulling out and I use bolts and nuts C³ to hold the rings firmly pressed together. When the time comes to finally close the 25 opening, I use a plate C⁴ held against the ring C by springs C⁵ surrounding screws C⁶ which are threaded in the ring C, a gasket C' being added to make a gas-tight joint.

In order that air may be forced into the 30 space between the forming bag A and the balloon structure B' B², I secure to the ring C, in an air-tight fashion, a flexible cloth pipe D' connected with the chamber D which is connected with an air-lock D⁴ having doors D² D³. By a suitable pump, which I have thought it unnecessary to show but which is connected with the chamber D, the air gradually passes to the place desired, and the air bag A gradually collapses. I may send men on the inside of the 35 balloon structure to gradually fold up the forming bag into a small and compact bundle as indicated in Fig. 7 while it is in process of collapsing. It is now time to coat the inside of the balloon with some cementing 40 substance or varnish which is impervious to the inflating gas, generally hydrogen. To this end it is best to disconnect the balloon now filled with compressed air from the air lock and inflating chamber D and to 45 close the aperture in the balloon with the plate C⁴. This will permit the balloon to be rotated in the apparatus described in my co-pending application above referred to, so that the workmen, who are operating on the inside of the balloon structure, may 50 always conduct their operations at the bottom where they have a footing. During the time they are at work, the inside of the balloon is filled with air under a pressure 55 sufficient to keep it from collapsing.

Although I may use any well-known material for the purpose of coating the inside of my balloon, I prefer to use a mixture of 60 gelatin and glycerin to which may be added

a little albumen to set the mass. I have discovered that even a very thin layer of such material is highly efficient in preventing the escape of gas, while its pliable nature is also of value for my purposes.

In case the inside of my balloon is coated with a substance which will adhere to the forming bag, when this is again inflated, I may cover the surface of this bag with French chalk or the like to prevent such adherence. This being understood, and it being assumed that the applied coating is sufficiently dry, the air lock D is put in place, the cover C⁴ is removed, the men are taken out of the balloon and the forming bag is 70 gradually inflated, it being desirable to send workmen on the inside of the forming bag to see that it inflates properly in all directions. The purpose of this inflation is to force all the air out of the inside of the balloon and at the same time to keep the balloon under a sufficient internal pressure to 75 prevent it collapsing.

The final step of my process consists in having the hydrogen supplied to the chamber D under sufficient pressure to pass between the outside of the forming bag A and the inside of the balloon structure, the air being permitted to escape at A², from the forming bag at the same time. Workmen 80 on the inside of the forming bag fold up the same, nicely, during this operation, and finally pass it down into the chamber D whereupon the cover C⁴ is put in place and the air lock is removed and the result is that 85 my balloon which consists of two cross layers of fabric, each containing longitudinal threads or wires together with a gas-tight coating on the inside is, substantially, in its finished state and carries its lifting quantity 90 of hydrogen under the appropriate pressure. The outside of the balloon may naturally be coated with any suitable substance as is the case with other balloons.

I claim:

1. The process of building a balloon of a collapsible type which is injured if collapsed which consists in inflating a forming bag, building the balloon thereupon, deflating the forming bag and simultaneously inflating 105 the balloon, and finally removing the forming bag, substantially as described.

2. The process of building and coating the inside of a balloon which consists in inflating a forming bag, building the balloon thereupon, deflating the forming bag and simultaneously inflating the balloon with air, and coating the inside of the balloon with a gas tight composition while the same is filled with air and the forming bag is 115 collapsed, substantially as described.

3. A process of building a balloon, coating the inside and inflating it with gas which consists in inflating a forming bag, building the balloon thereupon, deflating the 120

forming bag and simultaneously inflating the balloon with air, coating the inside of the balloon with a gas-tight composition, inflating the forming bag to expel the air from the balloon and finally filling the balloon with gas and simultaneously deflating the air bag, substantially as described.

In testimony whereof, I have signed my name to this specification, in the presence of two subscribing witnesses.

MELVIN VANIMAN.
